FRAME STRUCTURE

Felix E. Lang, Sayreville, N. J.

Application September 15, 1945, Serial No. 616,489

1 Claim. (Cl. 211—123)

1

This invention relates to lattice-like structures, such as, for example, music bar standards, display stands, frames and like articles of manufacture, and is concerned more particularly with an improved method and means of joining the cross-bars of the frame to their transverse supports.

A primary aim of the invention is to obtain an easily assembled yet firm and substantially rigid connection, between the several frame elements whereby to build into a structure of this character a high degree of resistance to twisting and to diagonally applied forces, with the use of a minimum quantity of material.

A further aim of the invention is to overcome certain inherent weaknesses and difficulties encountered in the manufacture and assembling of lattice-like structures, to simplify and reduce the operations involved in fitting and assembling the parts, and to render available an improved design of joint that not only is attractive from the ornamental aspect but which is also functionally superior and more stable than is the joint obtained when resort is had to conventional methods of fabrication.

As an example of the type of lattice-like structure to which the invention relates, reference will be made to a music bar or stand wherein five horizontally disposed bars (representing lines) are to be held in parallel spaced relation in end-standards or uprights. To lend attractiveness to the music stand, the horizontal bars are glass or plastic rods, and the notes, clef, and the various other music symbols are hung upon the rods. Because the rods vary somewhat in diameter it has been necessary heretofore to fit each end of each bar to a particular hole in the end standard to keep the stand in erect position which was not only costly and time consuming but made it impractical to box and ship a music stand except in its fully assembled condition. Moreover, and even tho the bars and their end pieces were individually fitted, the prior types of joint rarely were tight enough effectively to constrain the bars and the complete assembly against twisting or from slanting when in use.

The present invention undertakes to provide a firm joint for transversely extending members that automatically compensates for variations in sizes of the members and which has a clamping effect upon the individual elements, producing a substantially rigid self-sustaining structure without need for drilling and reaming or the use of auxiliary connectors. To achieve the objectives in view it is proposed to form each of the upright members of the frame of semi-rigid material and

2

preferably in two parts, each of which is pre-formed with a series of semi-circular shaped recesses spaced therealong. The recesses, in the case of a music bar stand, are uniformly spaced apart and are disposed alternately along each side of the standard. Two of such preformed elements, when placed in reversed position adjacent each other, constitute a single standard, and the alternated recesses in each being offset but their projected shapes forming cavities for the reception and support of the rods. When the rods are in place, the general effect is one of weaving, that is, each upright member appears as woven over and under the respective rods, with each of the uprights oppositely woven. When so related the frame elements mutually coact and function to grip the respective rods about a substantial portion of their perimeters. With a joint of this character, at least three upright members are required, one facing one way between two facing the opposite, but it is preferable to employ four members, two at each end of the music bar or stand, and additional uprights intervening if the expanse or area is relatively large.

Other objects and advantages will be in part indicated in the following description and in part rendered apparent therefrom in connection with the annexed drawing.

To enable others skilled in the art so fully to apprehend the underlying features hereof that they may embody the same in the various ways contemplated by this invention, a drawing depicting a preferred typical construction has been annexed as a part of this disclosure and, in such drawing, like characters of reference denote corresponding parts throughout all the views, of which—

Figure 1 is a front view of a music bar stand embodying this invention.

Fig. 2 is an enlarged view of a stand illustrating more clearly the interwoven character of the end standards.

Fig. 3 is an end view of Fig. 2.

The music stand disclosed in Figure 1 represents a typical application of the herein proposed method and means of firmly clamping a series of rods as to maintain the rods in parallelism and the stand as a whole in an erect non-slanting position. Briefly, the music stand comprises five horizontal bars 5, 6, 7, 8 and 9 (representing lines) and vertical end standards 14, 15 and 16, 17 (representing score bars). The musical clef 18, notes 19, etc., are hung upon the bars in any suitable way. Additional vertical bars, musical symbols, or other characters may be

mounted upon the bars according to taste or the subject matter being displayed. The horizontals 5-9 are, in the present embodiment, glass rods, and the end standards, musical symbols, etc. are made of plastic materials, such as "Lucite."

In constructing a lattice-like frame of this character considerable difficulty is encountered in joining the rods firmly in the end standards. The glass rods are not uniform in size nor uniform throughout their length and the drilling of holes in end pieces to receive the rods has not been practical because each rod required separate and individual fitting operations at each end. Any looseness at the joints rendered the frame unstable and a marked tendency toward leaning to one side resulted.

In an effort to overcome such problems and to simplify the construction as well, this invention proposes a frame construction in which the horizontal and vertical members mutually cooperate to clamp themselves firmly together, irrespective of the normal variations and irregularities in the size or shape of the several parts. The improved joint of this invention is composed of upright members 14, 15 (16, 17) each of which is generally rectangular in cross-section and pre-formed with a series of spaced semi-circular recesses 21, 22, 23, 24 and 25 in its opposite sides. The recesses alternate with one another, as illustrated in Fig. 3, the odd numbered recesses being in one side and the even numbered recesses being in the opposite side. Preferably each recess is of a radius slightly smaller than the rod to be gripped therein so that the uprights themselves have a clamping effect upon the rods which is amplified and increased when the uprights are tensioned. To tension the uprights each portion 26, 27, 28, 29 and 30 containing the alternated recesses of each upright, is initially depressed out of the general plane of the bar a distance slightly less than one-half the thickness of the rod to be seated and clamped therein and the intervening bridging portions 31, 32, 33 and 34 that connect the recessed portions of the bar, form rigid spacers and truss members.

When two of such uprights are placed adjacent to one another and oppositely facing each other, the alternated recesses in one upright complement the recesses formed in the other upright and together they form substantially circular openings for the reception of the rods 5-9. Where the bridging portions 31-34 of the uprights join the portions 26-30, the reverse bends in the upright members function as upper and lower abutments definitely locating and confining the horizontal rods against upward or downward movement.

In assembling a structure of this character, one pair of uprights, e. g., 14, 15 is first fitted with the lower (or the upper) three rods. Thereafter the other ends of the rods are pressed into a single plane and a third upright, e. g., member 16, is applied. By applying the upright members in alternation, similar to the weave of cloth, it will be found that three uprights and three rods form a self-locking self-retaining assembly. Thereafter additional uprights and rods may be added as may be desired or for which provision has been made.

By laterally offsetting the inside walls of the respective recesses 21, 22, etc., a distance slightly less than the thickness or the diameter of the

rods to be clamped therein, the inserting of the rods requires that each recessed portion of the uprights be sprung laterally a slight distance further, and the inherent elasticity of the stock, in tending to return to its normal position, effects a firm clamping of each rod at points above and below a horizontal diametral line, notwithstanding variations that may exist in rod sizes. As the rods are assembled, each alternated upright 5 is not only placed under tension, but that the recessed portions 21, 22, etc., thereof, are caused to grip the peripheries of the several rods and establish a plurality of regions of surface engagement therewith. In consequence, each rod becomes supported and clamped in a sleeve-like bearing, i. e., a bearing that extends from well below a diametral line to a point well above the diametral line, on each side of the vertical plane. This gives to each rod, firm surface support in each of the quadrants a, b, c, d, and the respective rods cannot, therefore, sag (out of parallelism) or assume a slantwise position. It has been found that glass rods approximately $\frac{3}{2}$ " in diameter are firmly held 1" apart if the end standards 10 are constructed of plastic materials measuring $\frac{5}{8}$ " x $\frac{1}{4}$ " with the $\frac{1}{4}$ " dimension extending lengthwise the rods. Three of such members 15 make a tensioned bearing aggregating $\frac{3}{4}$ " in length and which has been found well adapted to sustain the rods, and such symbols or characters as may be mounted thereupon, and the frame as a whole against untoward twisting or endwise leaning.

As illustrated in Fig. 3, each of the end standards 20 is provided with a leg portion 50, that conveniently is a continuation of the lowest rod bearing portion 26. By so fashioning the legs (when legs are desired) the weight of the assembled frame and parts carried thereby, further promotes the clamping action. The upper end of the uprights of the frame may be ended off where the portions 35 of two uprights cross one another. If desired a union can be made at that zone 25 by cementing or welding those portions together.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be, comprehended within the meaning and range of equivalency of 30 the following claim.

Having thus revealed this invention, I claim as new and desire to secure the following combinations and elements, or equivalents thereof, by Letters Patent of the United States:

60 In a music frame comprising a plurality of horizontally disposed glass rods spaced from one another and arranged in parallelism the combination of two supporting standards for gripping and maintaining said rods spaced from one another and in parallelism, each standard comprising two semi-rigid members each of which is transversely interwoven with the said rods and with the members of each of said pairs oppositely interwoven with the said rods and the lower extremities of 65 each of said members extending out of the general plane of the frame and forming leg elements.
